DOLL

Elsie Gilbert Winterfeld, New York, N. Y., assignor to Three-In-One Doll Corporation, New York, N. Y., a corporation of New York

Application December 15, 1945, Serial No. 635,329

7 Claims. (Cl. 46—151)

1

The present invention relates to dolls of the type having a rotating head which presents two or more, preferably three facial expressions, depending upon the position of the head relative to the body of the doll.

Dolls having rotatable heads provided with different facial expressions thereon as heretofore constructed and designed have invariably involved the use of a rigid or hard body capable of providing a bearing support for the rotatable shaft on which the head is mounted. Such rigid or hard bodies are objectionable not only because they are more easily damaged than soft bodies but also because for a given size doll they are heavier in weight, more costly to produce and more likely to cause injury to infants and small children. There is therefore a decided preference on the part of many adults and children for dolls having soft or "cuddly" bodies such as those made from cotton batting or similar soft stuffing material. To the best of my knowledge and belief no one has devised a doll prior to my invention having a soft "cuddly" body and a rotatable head presenting different facial expressions associated with said body so that the head may be freely rotated when desired requiring so little energy so to do that even a normal infant, say a year old, can readily manipulate the head and yet notwithstanding repeated rotation remain properly attached to the body and retain its attractive appearance.

It is an object of this invention to provide a doll having a soft body and a head provided with different facial expressions rotatable relative to said body, which head requires little effort to rotate it and yet, when moved to position to expose to view a desired facial expression, remains fixed in this position until the head is manually moved again, which head is movable relative to the soft body without injury or damage thereto and the parts of which doll are simple in design and construction and can readily be assembled even by unskilled labor so that the doll is relatively inexpensive.

Other objects and advantages of this invention will be apparent from the following detailed description thereof.

In accordance with this invention a doll is provided having a body stuffed with cotton batting or other fibrous or stuffing material providing a soft and "cuddly" body. Disposed within this body is a rigid bearing support, preferably in the form of a cylinder having an axial bore extending the full length of the cylinder and providing an extended bearing surface for a shaft rotatably

2

mounted therein. A sheet of fabric capable of receiving stitches is adhesively or otherwise secured to the bearing support and the cotton batting or other stuffing stitched or sewed to this fabric thus fixing the bearing support relative to the body so that relative movement of these parts is prevented. A head provided with different facial expressions on the peripheral surface thereof is fixed to one end of the shaft rotatably mounted in this bearing for rotation with the shaft and a hand-engaging member is secured to or made integral with the head or with the other end of the shaft which may protrude from the soft body so that by turning the same the head also turns due to the shaft being freely rotatable in the bearing support. In the case where the hand-engaging member is fixed to the head, a stop member, preferably in the form of a small ball, is secured to the other end of the shaft to prevent removal of the shaft and head carried thereby from the bearing support, the ball shape of the stop member permitting the ready rotation of the head without disturbing the packing or stuffing material forming the soft body of the doll when the hand-engaging member is manually manipulated. The head and ball stop are so mounted on the opposite ends of the rotatable shaft that they are in frictional contact respectively with the top and bottom of the cylindrical bearing member, and thus prevent undesired rotation of the doll head.

In the preferred embodiment illustrated on the drawing the invention is shown incorporated in a doll having on the peripheral surface of the doll head three different facial expressions and the present description will be confined to the present illustrated embodiment of the invention. It will be understood, however, that the novel features and improvements are susceptible to other applications such, for example, as a doll having a different number of facial expressions, and hence the scope of this invention is not confined to the embodiment herein described.

In the accompanying drawing:

45 Figure 1 is a fragmentary front elevational view of a doll embodying this invention, portions of the doll, namely, the legs and one arm being omitted since these parts may be of any conventional type and by omitting these parts the remainder of the doll embodying my invention may be shown on a somewhat larger scale;

50 Figure 2 is a vertical section through the doll of Figure 1;

55 Figure 3 is a horizontal section taken in a plane passing through line 3—3 of Figure 1; and

Figure 4 is a perspective view showing the doll head and the associated bearing support for the shaft on which the head is mounted.

Referring to the drawings reference character 10 indicates a doll head which may be of composition or other material employed in making doll heads which head has equally spaced about the circumferential periphery thereof three face simulating portions 11, 12 and 13 (Figure 3) each presenting a different facial expression. These three face simulating portions, for example, may simulate smiling, weeping and sleeping countenances. Doll head 10 is fixedly mounted on a cylindrical shaft 14 which desirably extends through the head, the end 15 thereof being fixed to a disc member 16 integral with or attached to the top of the head. Shaft 14 extends through a cylindrical bearing member 17 having an axial bore 17' of a diameter slightly greater than that of shaft 14 to provide an extended bearing support for the shaft 14 which is thus freely rotatable in this bearing member. Secured to end 18 of shaft 14 is a small ball 19 which maintains the assembly of head and shaft within the bearing member 17 preventing removal of this assembly from the bearing member. The doll head 10 and ball stop 19 are so mounted on shaft 14 that they are in frictional contact, respectively, with the top and base of the cylindrical bearing member 17 preventing undesired rotary movement of the doll head. By manual movement of disc 16, which manual movement requires little energy, the head may be readily rotated to any desired position. The bearing member 17 and the shaft 14 are desirably of wood but may be of any suitable material such as light metal, e. g., aluminum, or plastic.

Adhesively secured to the circumferential surface of the bearing member is a sheet of fabric 20 which desirably covers approximately the top half of the peripheral surface of this bearing member. Body 21 of the doll consists of an outer fabric 22 defining the outline of the body and stuffing or packing 23, which may be cotton batting or other fibrous or stuffing material, providing a soft "cuddly" body. The stuffing material 23 is sewed to the fabric sheet 20 on the bearing member 17 by means of stitches 24 which pass through the stuffing and the fabric. Preferably the top portion of fabric 21 defining the outline of the body is also secured by stitches 25 to the fabric sheet 20. Thus the soft body 21 is secured to the bearing member 17 so that relative movement is prevented and a bearing support for the shaft 14 carrying the head 10 is provided in which bearing support the shaft may freely rotate so that by applying little energy to the disc 16 the head can be moved to any desired position.

Secured to the top of the body is a hood 26 which, as shown in Figure 3, encloses approximately 180° of the surface of the head. Thus when any one of the facial portions 11, 12, 13 are in the position shown in Figure 1, where it is exposed to view, the other two portions are disposed within the hood 26 and hence are not exposed to view. Secured to this hood as by sewing are tufts of hair or hair simulating material 27, 28 and 29, tufts 27 and 28 being secured to the sides of the hood so that they extend along the sides of the face exposed to view and tuft 29 at the top of the hood so that it overlies the top of the head. A bow 30 may be associated with the hood, as shown in Figure 1, and the top por-

tion of the doll may be clothed with a jacket 31 or other suitable apparel and the bottom with legging 32 fragmentarily shown.

It will be noted that, due to the extended support provided by the axial bore 17' in bearing member 17 for shaft 14, head 10 can readily be manipulated by the top member or disc 16 to expose any desired facial expression to view requiring little or no energy to impart rotary movement to the head so that the doll can be operated even by a normal infant. Ball stop 19 permits rotary movement of the head without injury to the stuffing of the body and yet, due to the frictional contact between this stop and the head member and the base and top of the bearing member, the head is retained in position to which it is moved; moreover stop 19 prevents removal of the head and shaft from the bearing support 17. Furthermore the parts of the doll, it will be noted, are simple, can readily be manufactured at little cost, and in order to assemble the doll it is only necessary to place the shaft 14 carrying the head in the axial bore of bearing support 17, secure the stop member 19 to the end 18 of the shaft 14, sew the cotton batting or other stuffing to the fabric 20 and then clothe the resultant assembly. These operations it will be noted are of a type that can be carried out by unskilled labor.

Since changes may be made without departing from the scope of the invention, it is intended that the above description should be interpreted in an illustrative and not in a limiting sense. For example, instead of hand-engaging member or disc 16 being fixed to head 10, the top of the head may provide a bearing support for end 15 of shaft 14, which support is covered by hood 26, and the other end of shaft 14 may protrude from the soft body and be provided with a hand-engaging disc or other member which when turned causes rotation of the head and which prevents removal of the doll head and associated shaft from the bearing support 17. In this latter modification the hand-engaging member is preferably not exposed to view, for example, it could be disposed between the legs of the doll and covered by the dress or other article of apparel worn by the doll so that the doll may be held in one hand and the other hand used to rotate the doll head to change the facial expression.

What is claimed is:

1. In a doll, a body containing stuffing material so as to provide a soft body, a bearing member in the upper portion of said body, said bearing member having an opening therein, a fabric sheet secured to the exterior of said bearing member, said stuffing being secured to said fabric sheet so as to prevent relative movement of said bearing member and said body, a shaft rotatably mounted in said opening in said bearing member, and a head fixed to the shaft for rotation therewith, said head having a plurality of different facial expressions.

2. In a doll, a body containing stuffing material so as to provide a soft body, a bearing member in the upper portion of said body, said bearing member being elongated in the direction of the length of said body and having an opening therethrough extending in the direction of its length, a fabric sheet secured to the exterior of said bearing member, said stuffing being secured to said fabric sheet so as to prevent relative movement of said bearing member and said body, a shaft rotatably mounted in said opening in said bearing member, a head fixed to the

shaft for rotation therewith, said head having a plurality of different facial expressions, a hood covering the top, back and side portions of said head leaving exposed to view only one of said facial expressions, and a member fixed to the top of said head for rotating the head to change the facial expression exposed to view.

3. In a doll, a body portion stuffed with soft material to provide a soft "cuddly" body, a cylindrical bearing member having an axial bore extending from top to bottom thereof and disposed in the top of said body portion, a fabric sheet adhesively secured to said bearing member, said stuffing being sewed to said fabric sheet to prevent relative movement of the stuffing and the bearing member, a shaft mounted for rotary movement in said axial bore, a small ball stop member secured to one end of said shaft to prevent withdrawal thereof from said axial bore, a head having a plurality of facial expressions, said head being fixedly mounted on the other end of said shaft, and a member on the top of said head for rotating said head by causing said shaft to rotate in said axial bore.

4. A doll as claimed in claim 3 in which said head and ball stop are in frictional contact with said cylindrical bearing member to prevent undesired rotary movement of said head.

5. A doll as defined in claim 3, in which the cylindrical bearing member and shaft are of wood, the stuffing is cotton batting, the head is provided with three different facial expressions, and a hood is secured to the top portion of the doll to enclose the back and sides of the head leaving exposed to view only one facial expression thereon.

6. In a doll, a body portion stuffed with soft material to provide a soft "cuddly" body, a cylindrical bearing member having an axial bore extending from top to bottom thereof and disposed in the top of said body portion, a fabric sheet adhesively secured to said bearing member, said stuffing being sewed to said fabric sheet

to prevent relative movement of the stuffing and the bearing member, a shaft mounted for rotary movement in said axial bore, a small ball stop member secured to one end of said shaft to prevent withdrawal thereof from said axial bore, a head having a plurality of facial expressions, said head being fixedly mounted on the other end of said shaft, said head and ball stop being in frictional contact with said cylindrical bearing member to prevent undesired rotary movement of said head, a hood covering the head portion of the doll to enclose the back and sides of the head leaving exposed to view only one facial expression thereon, and a member on the top of said head for rotating said head by causing said shaft to rotate in said axial bore.

7. In a doll, a body portion stuffed with soft material to provide a soft "cuddly" body, a cylindrical bearing member having an axial bore extending from top to bottom thereof and disposed in the top of said body portion, a fabric sheet adhesively secured to said bearing member, said stuffing being sewed to said fabric sheet to prevent relative movement of the stuffing and the bearing member, a shaft mounted for rotary movement in said axial bore, a head having a plurality of facial expressions, said head being fixedly mounted on one end of said shaft, and a member on the other end of said shaft for rotating said head by causing said shaft to rotate in said axial bore.
